UNITED STATES PATENT OFFICE.

BENJAMIN LIPPER, OF PHILADELPHIA, PENNSYLVANIA, ASSIGNOR TO HIMSELF, AUGUSTUS A. LAZARUS, AND ISAAC A. SCHWARZ, OF SAME PLACE.

DESIGN FOR A DRESS-TRIMMING.

SPECIFICATION forming part of Design No. 21,575, dated May 24, 1892.

Application filed April 30, 1892. Serial No. 431,361. Term of patent 3½ years.

To all whom it may concern:

Be it known that I, BENJAMIN LIPPER, a citizen of the United States, and a resident of Philadelphia, Pennsylvania, have invented a new and original Design for a Dress-Trimming, of which the following is a specification,

My design is fully shown in the accompanying drawing, which represents a face view of a piece of the trimming.

10 The design comprises a central tape-like band *a*, narrow bands *b* on each side of said central band, opposite fan-like figures *d*, and a cord *f*, crossing the band *a* diagonally first in one direction and then in the opposite direction and forming loops *g* beyond each edge of said central band, these loops being disposed

between the fan-like figures *d*. These fan-like figures are composed of cord-loops of different lengths, and the figures along each edge of the trimming are connected by loops *i*, projecting 20 inward over the central band.

I claim—

The design for a dress-trimming, substantially as described, and as shown in the accompanying drawing.

In testimony whereof I have signed my name to this specification in the presence of two subscribing witnesses.

BENJAMIN LIPPER.
